United States Patent Office.

OTTO LINDEMANN, OF NEW YORK, N. Y.

Design No. 4,380, dated October 4, 1870.

DESIGN FOR THE LID OF A FEED-CUP IN BIRD-CAGES.

The Schedule referred to in these Letters Patent and making part of the same.

To all whom it may concern:

Be it known that I, OTTO LINDEMANN, of the city, county, and State of New York, have invented a new and original Design for the Lid of a Feed-Cup in Bird-Cages; and I do hereby declare the following to be a full, clear, and exact description thereof, which will enable those skilled in the art to make and use the same, reference being had to the accompanying drawing forming part of this specification, in which drawing—

Figure 1 represents a front view of my lid when the feed-cup has been removed.

Figure 2 is a transverse section of the same when the feed-cup is in its place.

Similar letters indicate corresponding parts.

This design represents an insect, the antennae of which are curved and made to catch over a rod in the frame of the cage in such a manner that when the feed-cup is in position, the insect appears to rest on the edge thereof, and, when the feed-cup is removed,

the insect drops down and covers the aperture made vacant by the removal of the feed-cup.

In the drawing—

The letter A represents an insect, the wings of which are spread and the antennae *a* of which are curved or hook-shaped, and made to catch over the rod *b* in the frame of the bird-cage.

When the feed-cup is in position, as shown in fig. 2, the insect A appears to rest upon the edge of said cup, and when the feed-cup is removed the insect drops down to the position shown in fig. 1, and the aperture left vacant by the removal of the feed-cup is closed automatically.

What I claim as new, and desire to secure by Letters Patent, is—

The design for the lid of a feed-cup in bird-cages, as shown and described.

Witnesses:
